UNITED STATES PATENT OFFICE.

REINHOLD M. WENDEL, OF STOCKHOLM, SWEDEN.

BEATING ENGINE.

Application filed May 23, 1927, Serial No. 193,683, and in Sweden May 25, 1926.

This invention refers to beating engines of the class which is employed in the paper mill factories. The main object of this invention is to provide a beating engine which 5 procures the treating of the fibres with a considerable reduced waste of driving force.

Another object of this invention is a beating engine which can treat a fibre mass of a higher concentration than what is possible 10 in the beating engines hitherto known.

A further object is a beating engine which can operate continuously, thereby reducing the number of beating engines which is necessary to suit the increased capacity of the 15 modern paper machines.

Further features of this invention and how same is to be carried out will be clearly described below and illustrated in the annexed drawings. Said drawings have the 20 purpose to demonstrate diagrammatically how the invention can be materialized, but they do not show in detail all such parts and devices which are necessary to make the drawings suited for the work shop, because 25 the constructional design of the improved beating engines can be varied between wide limits within the scope of this invention.

In the drawings:

Fig. 1 is an elevated section of the prototype of the improved beating engine,

Fig. 2 is an axial section of the same apparatus,

Figs. 3 and 4 are corresponding views of a somewhat modified embodiment of the beating engine,

Fig. 5 is an axial section through a distributor for the mass within the machine,

Fig. 6 a plan view of the same distributor.

Figs. 5 and 6 are drawn on a somewhat enlarged scale in comparison with the other figures,

Fig. 7 is the same view as Figs. 1 and 3 of a further modification,

Fig. 8 is a portion of an axial section of 45 the embodiment shown in Fig. 7,

Figs. 9 and 10 are views corresponding with those in Figs. 1 and 2 respectively but of a further embodiment of the invention,

Fig. 11 is a portion of the same section as 50 in Fig. 10 but illustrating a modified arrangement thereof, and

Fig. 12 is a longitudinal view of roll and bed plate divided in four sections.

In all the drawings the same reference figures refer to similar parts throughout.

Referring to the drawings 1 represents the

trough of the beating engine which trough differs from what is generally known in beating engines in so far, that the trough 1 is designed as a cylindrical drum with a substantially horizontal axis. This drum can be supported in any arbitrary way with the non-dispensable condition, that the drum must be able to revolve about said axis. In the embodiments illustrated in Figs. 1-2 and 60 9-10 the drum is supported on rollers 2 stationarily mounted upon the floor or any suitable ground, whereby the shell of the drum ought to be provided with some rails or other suitable strengthenings 200 around its 70 outer surface. In Fig. 4 the drum 1 is shown as provided at both bottoms 32 with central necks 320 designed as hollow pins of a somewhat large diameter and adapted to cooperate with roller bearings 20, mounted 75 on stanchions 210 for the support of the drum. It is understood, that the same arrangement belongs to the embodiments shown in Figs. 3 and 7, though the details are not shown in order to avoid accumulation of parts which nevertheless can be easily understood.

Within the rotary drum 1 there is disposed a roll 3 of substantially the same character as the roll in ordinary beating engines, 85 though some special modifications from said ordinary form will be dealt with herebelow. The roll 3 is supported by a horizontal shaft 4, carried by bearings 5 at the ends which bearings are supported in any suitable way, 90 for instance, as described in the following paragraph. Said shaft 4 is provided with a pulley 6 for its revolving with the roll 3.

Below the roll 3 the bed plate 7 is disposed. This bed plate can be designed in 95 substantially the same way as the bed plates in ordinary beating engines, but with reference to Figs. 9 and 10 some modifications will be described later on. The suspension of the bed plate 7 in relation to the roll 3 100 may be such that the interspace 9 between the bed plate and the roll can be adjusted according to the degree of treatment of the fibres. In Figs. 1, 2 and 3, 4 as well as 7 this adjustable suspension is illustrated as 105 consisting therein, that the bed plate 7 is stationarily supported by the stanchions 210 and the bearings 5 carried by a couple of levers 34, the one end of which is pivotably supported by a stanchion 340 and the opposite end by a flexible wire 354, which is laid round a sheave 351 and loaded in the free

end by a counterweight 35. The sheave 351 can be revolved by means of a crank 353 and toothed gear 352. A stanchion 350 supports the sheave 351 and gear 352 and consequently the corresponding end of the levers 34 and the roll 3. When revolving the sheave 351 with the crank 353 the roll 3 can be lowered or lifted in relation to the bed plate 7 for adjusting of the interspace 9 therebetween in the requisite degree.

In Fig. 1 the outlet end 8 of the bed plate 7 is raised a certain height above the intake end 10 thereof, and the interspace 9 between roll and bed plate somewhat enlarged to the end 8. In the same figure as well as in Figs. 2 and 7 the roll shaft 4 is substantially central to the axis of the drum 1 but in Figs. 3, 4, 9 and 10 said shaft is mounted eccentrically to the axis of the drum. Roomy openings between the shaft 4 and the necks 320 allow for the supply of the mass to be treated into the drum whereby in Fig. 2 a funnel 15 is shown for this supply.

In Figs. 3 and 7 a removable cover 13 is arranged in the shell of the drum 1 for the supply, and in all the Figs. 1, 2 and 3, 4 as well as 7 another removable cover 14 on a remote spot of the shell of the drums is provided for the discharge of the ready-made product, which escapes through a funnel 140 in the floor.

In Figs. 9 and 10 the side bottoms 32 are reduced to only rather narrow flanges 32^a without the aforesaid necks 320 thus leaving the main portion of the drum ends 1' and 1'' open for free passage into the drum, whereby the supply is effected through a pipe 150 near the bottom at the left hand end 1' of the drum 1 and the discharge through a pipe 151 on the right hand end of the drum somewhat above the bottom as will be more clearly described below.

In Fig. 4 a pulley 33 on the one hollow pin 320 is shown for the revolving of the drum 1, and it is understood, that similar appliances or adequate ones can be provided for in the other embodiments of the invention. For instance in Figs. 9 and 10 the two rollers 2 at the one side of the drum 1 may be mounted on a common shaft 331 which at the one end is provided with a pulley 330 which can be rotated by a belt from the driving motor and thus effects the rotating of the drum 1 in the same direction as the roll 3.

In Figs. 3 and 4 the interior of the drum 1 is provided with series of shovels or scoops 16 along the shell near the side bottoms 32. At the intake end 10 of the interspace 9 a funnel 17 terminates the upper portion of which forms a collector for the pulp mass which is carried up by means of the scoops 16 and delivered into the collector funnel 17. A slide 25 in the lower part of funnel 17 can vary the outflow from the funnel into

the space 9 and thus regulate the fluid column 26 in the funnel 17. The funnel 17 is provided with sloping false bottoms 18, so that the pulp mass taken from the two opposite side portions of the drum 1 by the scoops 16 may be delivered upon the centre portion of the roll 3 and thus thoroughly mixed. This mixing of the mass can be further effected by means of the device shown in Figs. 5 and 6 wherein the sloping false bottoms 18 are substituted by two oblique channels 22 crossing each other and leading each from a pocket 21 in the upper part of the funnel 17, so that the mass discharged from the left hand side of the drum 1 becomes fed to the right hand portion of the roll 3 and vice versa.

In Figs. 7 and 8 the scoops 16 and funnel 17 are substituted by guide plates 17' and 17'' the former of which begins near the shell at a certain distance from the uppermost portion of the drum 1 with a bent edge 30 and passing across the drum above the roll 3 terminates lower down near the shell while the other guide plate 17'' begins with a bent edge 31 near the shell at some distance below the edge 30 of the guide plate 17' and goes down to the intake end 10 of the space 9 below the roll 3. The edge 30 lies somewhat further away from the shell of the drum than does the edge 31 for the purpose mentioned below. From the discharge end of the bed plate 7 another guide plate 29 bent along a suitable curve ends below the end of the guide plate 17'. No one of the guide plates 17', 17'' and 29 takes part in the rotation of the drum 1 but are kept stationary by means of suitably arranged fixtures not shown in the drawing, as they can be designed in any arbitrary way as easily understood by those skilled in the art. Similar guides 17', 17'' and 29 are provided in the Figs. 9 and 10 but differ in certain degrees as will be clearly described below.

In describing the operation of the apparatus I will take the various embodiments in the same order as they are illustrated, and accordingly I will begin with Figs. 1 and 2. Here the drum 1 has no special driving means, but it is arranged centrally with the roll 3, which is positively revolved from some motor by a belt and the pulley 6.

When the pulp mass has been made liquid by a suitable mixing with water and supplied into the drum 1 through the funnel 15 to a height just below the roll 3—the removable cover 14 of course must be previously shut—the roll 3 is made to revolve in the direction indicated by the arrow in Fig. 1. This revolving of the roll 3 causes the pulp mass to enter the space 9 between roll and bed plate as known in beating engines of the ordinary types and raised a little above the stationary level of the mass in the drum on account of the raised end por-

tion 8. This increased liquid level on the rear side of the roll constitutes a force sufficient to drive the mass backwards to the intake end 10 of the space 9 just as the arrows in the lower portion of Fig. 1 illustrate. The friction between the mass and the shell of the drum 1 causes the drum to take part in the movement of the mass in the direction of the last mentioned arrows, e. g. in the opposite way relatively to the revolving of the roll 3, which revolving of the drum becomes facilitated by the rollers 2.

In the embodiment shown in Figs. 3 and 4 the drum 1 is positively rotated from a motor 15 and a belt on the pulley 33 whereby the moving direction of the drum is indicated by the arrow on the left hand side of the drum in Fig. 3, when the roll 3 is revolved as mentioned before in the opposite direction, indicated by the arrow just above the roll 3 in Fig. 3. The rotation of the drum causes the scoops 16 to catch portions of the pulp mass from the bottom of the drum and to carry it to the upper part thereof where the mass is discharged into the funnel 17, respectively into the pockets 21 shown in Figs. 5 and 6. From said funnel or its pockets the mass is discharged at 10 into the interspace 9 between roll and bed plate and thereby treated 20 in the known manner whereupon it is discharged in the main body of the mass at the rear side of the drum. The advantages of this embodiment of the machine lie therein, that on the one side the increased liquid 25 column 26 in the funnel increases the static pressure and thus increases the velocity of the mass when passing the roll and bed plate whereby the operative capacity of the machine will be enlarged, while on the other 30 side the sloping false bottoms 18 respectively the sloping and crossing channels 22 have a considerably good effect on the mixing of the mass thus also increasing the capacity of the machine.

In Figs. 7 and 8 the roll 3 and the drum 1 are both revolved positively similar as described for Figs. 3 and 4, but both in the same direction. However the speed of revolving of the drum is adjusted in accordance with the concentration and specific gravity of the mass in such a way, that when in equilibrium the pulp mass is carried in the shape of a rather thin layer 27 around the shell of the drum under a certain degree 55 of separation on account of the centrifugal force. By that another layer 28 of comparatively pure water becomes formed inwardly of the heavier mass layer 27. The guide plates 17', 17'' are disposed so that the bent edge 30 of the guide plate 17' catches the pure water layer 28 and carries it through the drum rearwards, so that it will be discharged just above the spot, where the mass, caught by the bent edge 31 of the 60 other guide plate 17'', is discharged by the

assistance of the guide plate 29 after its passage between roll 3 and bed plate 7 through the space 9.

From Fig. 8 it is visible, that the guide plate 17'' is somewhat narrower than the drum 1, so that it enters only the middle portion 27' of the mass layer 29, while the other guide plate 17' has substantially the same width as the drum 1. Hence a mixing of the mass is effected at the discharge ends 75 of the guide plates 17' and 29. Preferably the guide plates 17' and 17'' may be adjustable, so that their submerging into the layers 27 and 28 may be varied in accordance with the degree of concentration of said layers whereby the effect of the apparatus may be influenced.

The embodiments now described must all be stopped when the mass has been ready treated, so that the mass can be discharged 85 through the removable cover 14 and channel 140 and a fresh charge supplied. In contradiction to that the embodiment illustrated in Figs. 9-11 operates continuously 90 and does not need be stopped either for filling or for discharging. For that purpose the fresh mass is supplied through the rather narrow pipe 150 near the bottom at the left hand side of the drum 1, whereby 95 said supply is arranged such, that the flow can go on uninterruptedly during the revolving of the drum. It is to prefer, that the drum 1 with roll 3 and bed plate 7 be made of a comparatively more extensive axial length than in the beforementioned embodiments, whereby the roll as also the bed plate 100 preferably are provided with treating members of different shape on different portions of their length. The purpose of that is, that the mass when passing between roll and bed 105 plate shall be treated in various degree whereby one degree of treating takes place when the mass passes the first portion of the roll and bed plate another degree of treating occurs when the next portion of said 110 members is passed, and a further degree of treating when the following portion thereof is passed.

For the said purpose the roll 3 is supported in stationary bearings 5 but the bed plate 115 7 divided into a plurality of sections. In the drawing four such sections are designated viz, with 7^a, 7^b, 7^c and 7^d respectively as clearly to be seen in Fig. 12. These sections are supported each by an independent 120 adjusting mechanism, which can be designed in any arbitrary way and is not shown in the drawing to avoid confusion of lines so much more, as the designs of said adjusting appliances do not make part of this invention. They must however be arranged such that each section of the bed plate 7 can be adjusted relatively to the roll independently of the other sections.

Another arrangement for the same pur- 130

pose is, that the machine is designed so that the mass is supplied through the pipe 150 in the form of a rather narrow jet which is caused to pass from the inlet end 1' to 5 the outlet end 1" along a line which substantially equals a screw line whereby the mass for each turn passes the roll and the bed plate substantially under maintaining of the initial narrow jet. By these means each 10 portion of the mass is caused to pass all the variously designed sections of bed plate and roll and as a consequence becomes treated extraordinarily completely in one and the same machine during a continuous motion. 15 The screw line movement is accomplished thereby, that the guide plate 29 on the outlet side of the bed plate is formed as narrow channels each of somewhat the same width as the jet discharged from the inlet 20 pipe 150 and which channels are disposed obliquely to the vertical centre plane of the machine, so that the discharge end of each channel in plate 29 registers substantially with the inlet end of the next channel. The 25 large openings 1', 1" in the ends of the drum allow only a rather thin layer of mass to be present in the drum viz, at most as deep as the width of the flanges 32^a, and when revolving the drum 1 carries said layer 30 along with the shell whereby the friction between shell and mass serves as the transporting force. This layer of mass however becomes constituted by the narrow jets which have left the oblique channels in 35 guide plate 29, but as there are no positive partition walls along the shell said jets of course will somewhat flow out into the adjacent jets. Owing to the frictional and centrifugal force however such intermingling 40 of the jets becomes rather inappreciable.

A better result can be obtained, if the shell be provided with a plurality of small flanges or cams as designated with 171 in Fig. 11, whereby channels 170 are formed of substantially the same width as the channels in 45 plate 29. The channels 170 however must not be positioned obliquely but can be parallel to the radial planes of the drum.

The last channel in guide plate 29 terminates in the outlet pipe 151.

Guide plates 17', 17" of substantially the same character as the corresponding guide plates in Fig. 7 are present whereby the upper guide plate 17' terminates in a trough 55 172 which ends in a discharge pipe 173 on the outlet side of the drum. The guide plate 17" catches the water layer 28 from the drum shell and delivers it into the trough 172 from where it can be delivered back 60 into the drum 1 or carry away through the pipe 173, if a higher degree of concentration be wanted. Guide plate 17" catches the fibre layer 27 and carries it into the space 9 between roll and bed plate.

65 The treating members on the roll 3 and

section 7^a of bed plate 7 may be directed rearwards to soften their influence on the mass. The next portions of roll and bed plate may have more operative treating members and the last portions can be still 70 more effective. Hence the mass supplied through the pipe 150 at the left hand end of the drum leaves the drum on the right hand end through the pipe 151 after a very thorough treatment from the least to the most effective one. The machine can continue to work uninterruptedly the whole work day without need for stoppages for charging and discharging, and the mass can be ready made 75 in one and the same machine, thus saving 80 a considerable amount of cost and labour.

What I claim is:

1. In a beating engine, a rotary roll with a substantially horizontal axis, a bed plate cooperating with said roll, a drum with a substantially horizontal axis enclosing said roll and bed plate, said drum rotatory about said axis which is substantially parallel to the axis of said roll, means to supply the mass to be treated into said drum, means to discharge the ready treated mass therefrom and means to rotate said roll and said drum.

2. In a beating engine, a rotary drum with a substantially horizontal axis, a rotary roll therewithin with its axis of rotation parallel to the axis of said drum and cooperating with a bed plate within said drum, means to adjust the distance between roll and bed plate, and means to revolve drum and roll independently of one another, means to supply the mass to be treated into said drum and into the space between roll and bed plate and means to discharge the ready treated mass from the drum, means to mix the mass within the drum during its passage through the machine and means to regulate the supply of mass to the interspace between said roll and bed plate when operative.

3. In a beating engine, a rotary drum with a substantially horizontal axis, a rotary roll therewithin with its axis of rotation parallel to the axis of said drum and cooperating with a bed plate within said drum, said bed plate divided into sections with different operating members, means to adjust said sections independently of one another with relation to said roll, said roll provided with operating members of various forms on various portions of its length suited to cooperate with the variously designed bed plate sections, means to supply the mass to be treated into said drum at one end thereof and to discharge the ready made mass from said drum at the other end thereof, said means of supply and discharge adapted to act also when the drum revolves, and means to guide the flow of mass in a continuous motion from the intake end of said

drum to the outlet end thereof whereby the mass is caused to pass the interspace between roll and bed plate sections successively from the one end thereof to the other along all 5 the variously formed portions of roll and sections of bed plate, and means to revolve said drum and said roll independently of one another.

4. In a beating engine, a rotary drum with 10 a substantially horizontal axis, a rotary roll therewithin with its axis of rotation parallel to the axis of said drum and cooperating

with a bed plate within said drum, means to revolve drum and roll independently of one another, means to supply the mass to be 15 treated into said drum and into the space between roll and bed plate, means to carry away the superfluous water from said drum when revolving, and means to discharge the ready treated mass from the drum. 20

In testimony whereof I have affixed my signature.

REINHOLD M. WENDEL.
